UNITED STATES PATENT OFFICE.

WILLIAM TANK, OF NEW ORLEANS, LOUISIANA.

BAKER'S OVEN.

No. 853,748.

Specification of Letters Patent.

Patented May 14, 1907.

Application filed November 28, 1906. Serial No. 345,425.

To all whom it may concern:

Be it known that I, WILLIAM TANK, a citizen of the United States, residing at New Orleans, in the parish of Orleans and State of 5 Louisiana, have invented new and useful Improvements in Bakers' Ovens, of which the following is a specification.

My invention pertains to ovens and more particularly to bakers' ovens; and it has for 10 one of its objects to provide in an oven a furnace having a plurality of linings of fire-clay or other fire-resisting or fire-proof material, this being advantageous for the reason that when the innermost lining is burned out or 15 broken or otherwise impaired, said innermost lining may be torn out and the furnace used with the other lining or linings, thus obviating the necessity of tearing down and rebuilding the oven after a short period of 20 use, and the loss of time and production incident thereto.

Another object of the invention is the provision in a baker's oven, of a construction for 25 efficiently disseminating heat under the baking surface and chamber with a view of uniformly heating said surface and chamber and avoiding undue heating of the same at the center, as frequently occurs with the result that the bread or other substance being 30 baked at such point is burned.

Other objects and advantages of the invention will be fully understood from the following description and claims when the same are 35 read in connection with the accompanying drawings, forming part of this specification, in which:

Figure 1 is a longitudinal, vertical section of the baker's oven constituting the present and preferred embodiment of my invention. 40 Fig. 2 is a transverse section of the oven taken in a plane extending through the furnace or fire box. Fig. 3 is a horizontal section on a reduced scale illustrating the passages intermediate the lower and upper longitudinal flues of the oven. Fig. 4 is a vertical cross-section taken in the plane indicated by the line 4—4 of Fig. 1.

Similar letters designate corresponding parts in all of the views of the drawings, referring to which:

A is the base of my novel baker's oven, which is preferably, though not necessarily, of concrete.

B is the ash pit of the oven, and C is the 55 furnace or fire box which has a mouth a formed by a metallic frame and also has a

grate made up, by preference, of a transverse metallic bar b, longitudinal, spaced bars c removably arranged on the bar b and the fire-clay section d at the back of the ash-pit, and a section e, of fire-clay or other refractory material, removably arranged on the frame a and the bar b. The removable spaced bars c and refractory section e are obviously susceptible of being readily replaced 65 with new parts when burned out or broken.

In addition to the mouth a and the grate, the furnace or fire-box C is provided with an inner lining D, of fire-clay or other refractory or fire-resisting material, and an outer lining 70 E, also of fire-clay or other refractory or fire-resisting material. The outer lining E extends down to the bottom of the ash-pit B and rearward over, under and at the sides of the longitudinal-central combustion chamber 75 F which extends rearward from furnace or fire-box C, while the inner lining D rests in the furnace or fire-box C alone, and on the shoulders f with which the outer lining E is provided. Thus it will be apparent that 80 when the inner lining D is burned, broken or otherwise impaired it may be readily broken and removed without the necessity of tearing down the oven or otherwise impairing the same. The removal of the inner lining 85 D will leave the oven with the outer lining E and it will be appreciated that such removal of lining D will prolong the usefulness of the oven as a whole without diminishing the efficiency of the same.

About the proportional distance illustrated above the furnace C and combustion chamber F is arranged the baking chamber G which, by preference, has its mouth h arranged below and slightly rearward of a vapor 95 flue i. The baking chamber G has a bottom wall k of fire-clay or the like, and below this wall k and in a dead-air chamber H above the furnace C and combustion chamber F is a wall I having depending transverse portions 100 J at intervals in its length. These depending transverse portions J form heat traps K which assist the dissemination of heat under the baking surface and assure said surface being uniformly heated with the result that 105 there is no liability of bread or other substance located on the center of the surface being burned.

The top of the baking chamber G is preferably formed by a wall L comprising transverse rails m and sections n, of fire-clay or analogous material, carried by said rails; and

above said wall L is a plurality of longitudinal flues M, and two cross-flues N N', which latter communicate with the flues M.

At opposite sides of the furnace C and 5 combustion chamber F are longitudinal flues P, Figs. 2 and 4, which are connected through openings r and s with the furnace C and combustion chamber F, respectively. The flues P are also connected through up- 10 right flues P³, Figs. 3 and 4, with the cross flue N. The cross flue N' is connected in the usual manner with a chimney or uptake Q as is also a cooling flue R leading from the baking chamber G, which cooling flue is con- 15 trolled by a damper S.

From the foregoing it will be understood that the products of combustion will pass from the furnace C and combustion chamber F through openings r and s, respectively, 20 into the longitudinal flues P, and from the latter will pass upward through the upright flues P³ to the cross flue N. From this latter flue N the products of combustion will pass through the longitudinal flues M and the 25 cross flue N' to the chimney or uptake Q.

T is the masonry portion of the oven and U is the usual filling of refractory material arranged in the top of the masonry portion.

The general operation of my novel baker's 30 oven is similar to that of an ordinary baker's oven and need not therefore be described in detail.

It will be gathered from the foregoing that while my improvements contribute consider- 35 ably to the durability and efficiency of a baker's oven they do not materially increase the cost of the same.

The construction herein shown and de- 40 scribed constitutes the preferred embodiment of my invention, but I desire it under- stood that such changes in the form, con- struction and relative arrangement of parts may be made in practice as fairly fall within 45 the scope of the appended claims, without departing from the spirit of my invention.

Having described my invention, what I

claim and desire to secure by Letters-Patent, is:

1. A baker's oven comprising a baking chamber, a furnace or fire-box arranged under the baking chamber, and a combustion chamber extending rearward from the furnace or fire-box and also arranged under the baking chamber; the said furnace or fire-box being provided with an outer fire-resisting lining and an inner fire-resisting lining which inner lining is independent of the outer lining and is arranged to be removed without detriment to the latter and without affecting the 50 operation of the oven.

2. A baker's oven comprising a furnace or fire-box, an ash-pit disposed below said furnace or fire-box, a combustion chamber extending rearward from the furnace or fire-box, an outer lining of fire-resisting material 55 extending over, under and at the sides of the combustion chamber and also extending above and down at the sides of the furnace or fire-box and the ash-pit and having shoulders at opposite sides of the furnace or fire- 60 box, and an independent inner lining of fire- 70 resisting material resting on the shoulders of the outer lining and independent of said outer lining.

3. The combination in a baker's oven, of a 75 furnace or fire-box, a combustion chamber extending rearward from said furnace or fire-box, a baking chamber disposed above the furnace and combustion chamber, a closed or dead-air chamber intermediate the furnace 80 and combustion chamber and the baking chamber, and transverse portions depending from the upper wall of the closed or dead-air chamber at intervals in the length of said wall, and serving to form heat traps. 85

In testimony whereof I have hereunto set my hand in presence of two subscribing witnesses.

WILLIAM TANK.
